UNITED STATES PATENT OFFICE.

CLARENCE D. PLATT, OF BRIDGEPORT, CONNECTICUT.

DESIGN FOR AN ELECTRIC-SWITCH MEMBER.

Application filed July 15, 1925. Serial No. 14,097. Term of patent 14 years.

To all whom it may concern:

Be it known that I, CLARENCE D. PLATT, a citizen of the United States, residing in Bridgeport, Fairfield County, and State of Connecticut, have invented a new, original, and ornamental Design for Electric-Switch Member, of which the following is a specification, reference being had to the accompanying drawing, forming a part thereof.

Fig. 1 is a perspective view of an electric switch member embodying my new design.

Figs. 2 and 3 are side and end views respectively showing a switch member of my design on a smaller scale.

Fig. 4 is a plan view of the member.

Fig. 5 is a sectional view of the member.

I claim:

The ornamental design for an electric switch member substantially as shown.

CLARENCE D. PLATT.
